(57) **CLAIM**

The ornamental design for a juicer cup as shown and described.

DESCRIPTION

FIG. 1 is a top, front perspective view of a juicer cup showing my new design;

FIG. 2 is a front view thereof;

FIG. 3 is a rear view thereof;

FIG. 4 is a left side view thereof;

FIG. 5 is a right side view thereof;

FIG. 6 is an enlarged top view thereof;

FIG. 7 is an enlarged bottom view thereof;

FIG. 8 is a bottom, rear perspective view thereof;

FIG. 9 is an enlarged detail view taken from portion 9 of FIG. 3;

FIG. 10 is an enlarged detail view taken from portion 10 of FIG. 6; and

FIG. 11 is an enlarged detail view taken from portion 11 of FIG. 6; and,

FIG. 12 is an enlarged detail view taken from portion 12 of FIG. 8.

The broken lines in the drawings depict portions of the juicer cup that form no part of the claimed design. The broken lines encircling portions of the juicer cup in FIGS. 3, 6, 8 and illustrated in enlarged views in FIGS. 9-12 form no part of the claimed design.

1 Claim, 12 Drawing Sheets
